UNITED STATES PATENT OFFICE.

JOHN P. THOMPSON, OF FALL RIVER, ASSIGNOR OF ONE-HALF TO THE WHITIN MACHINE WORKS, OF WHITINSVILLE, MASSACHUSETTS.

MACHINE FOR CARDING FIBROUS MATERIALS.

SPECIFICATION forming part of Letters Patent No. 443,414, dated December 23, 1890.

Application filed August 29, 1887. Serial No. 248,129. (No model.)

To all whom it may concern:

Be it known that I, JOHN P. THOMPSON, of Fall River, in the county of Bristol and State of Massachusetts, have invented certain new and useful Improvements in Machines for Carding Fibrous Material, of which the following is a full, clear, and exact description, reference being had to the accompanying drawing, forming part of this specification.

10 The drawing is a sectional view showing the relative positions of the new parts and their relation to the old parts of the carding-engine as usually constructed.

15 In the drawing, A represents the lap-roll, or roll of lapped fiber.

B B are the feed-rolls by which the lap is supplied and fed to the carding-engine.

20 C is the licker-in by which the lap is opened and the fiber cleaned.

D is a carrier-cylinder by which the fiber is taken from the licker-in and is carried to the doffer-roll E.

F represents a doffer-comb.

25 G G are auxiliary feed-rolls, and H is the main cylinder of a carding-engine. The rolls or cylinders C, D, E, and H are covered with card-clothing, as is usual with rolls or cylinders for carding-engines. The licker-in, the rolls, cylinder, and doffer-comb are driven 30 in the usual manner.

35 Cotton or wool or other fibrous material has been heretofore presented to the carding-engine in the form of a lap or sheet, and this sheet has been torn into fiber and the fiber more or less straightened by one or more rolls or cylinders covered with card-cloth. The fiber so opened out is then presented in that loose fibrous condition and the carding continued with flats and combing or working 40 cylinders. By this method the large main cylinder cannot do its full share of work, nor can it deliver the fiber evenly to the flats or other workers, as the slightest variation in the air-drafts will deliver much more or less fiber 45 on one portion of the main cylinder than on the other.

My improvement consists in mechanism for opening, straightening, and cleaning the fiber of the lap as much as is desired, such

as the licker-in and one or more card-clothed 50 cylinders for doffing the fiber and then for forming the same into a sheet or lap and presenting the sheet or lap to the main cylinder, as more fully described hereinafter.

To enable others skilled in the art to understand more clearly the nature of my invention, I will describe the same with reference to the accompanying drawing.

55 The roll or lap A is a roll of lapped fiber as it comes from the lapper, and is in the same condition as the ordinary lapped rolls. The sheet of lapped fiber I pass between the feed-rolls B B and present the same to the action of the licker-in C, by which the lapped fiber is opened, partially straightened, and also partially cleaned. The fiber so opened is delivered to the carrier D and carried to the doffer-roll E. The fiber is here in a loose and divided condition, and I have found in practice that the main carding-cylinder is not 60 evenly or uniformly through its whole width made to operate upon the fiber, and also that in all methods as heretofore practiced for delivering the fiber to the main cylinder the fiber has always been presented in a loose 65 open condition to the main cylinder, and when so delivered the main cylinder is not supplied uniformly with fiber. To avoid this difficulty and also to present the fiber in a 70 dense condition and hold the same so that the wires of the main cylinder can act to the best possible advantage on the fiber, I comb the fiber off from the doffer-roll E by means of the doffer-comb F or any other equivalent device, and form the fiber into a sheet, which 75 sheet I pass between the rollers G G, and thus present the sheet to the main cylinder, supplying the wires across the whole width of the cylinder uniformly with fiber held in a sheet between the rolls G G. By this means 80 the large or main cylinder is supplied with fiber evenly across its whole width, and all the subsequent working of the fiber is more 85 uniformly effected.

85 I have shown one way in which my invention can be carried out; but it will be evident to any one versed in the art that any arrangement by which the fiber after it has been

opened by the licker-in is again consolidated into a sheet or lap and this lap or sheet presented to the main carding-cylinder will secure the benefits of my invention.

5 Having thus described my invention, I claim as new and desire to secure by Letters Patent—

In a carding-engine, the combination, with the feed-rolls B, the licker-in C, the carrier-

cylinder D, and the main cylinder H, of the doffer E, the doffer-comb F, and the feed-rolls G, placed between the carrier-cylinder D and the main cylinder, as and for the purpose herein described.

JOHN P. THOMPSON.
